FIG. 4

UNITED STATES PATENT OFFICE

2,385,305

POLE SLIDE PROTECTOR

William L. Seide, Rochester, N. Y.

Application April 27, 1945, Serial No. 590,651

2 Claims. (Cl. 227—41)

The present invention relates to new and useful improvements in pole slides for firemen, and more particularly to a protector positioned at the bottom of the pole to prevent persons from standing in the way of firemen when sliding down the pole.

In fire engine houses it is the practice to provide a pole slide extending from the sleeping quarters to the main floor of the building and down which the firemen are accustomed to slide to enable them to more quickly reach their stations on the fire apparatus at the main floor of the building and frequently injury has been caused to persons standing at the bottom of the pole in the path of the descending firemen.

It is accordingly an object of the present invention to provide a protector at the bottom of the pole and which will prevent persons coming into close contact with the pole in the path of the descending firemen.

More specifically, the invention embodies an upstanding sleeve or chamber surrounding the bottom of the pole and into which the firemen drop during descent on the pole together with trip-actuated counterbalancing means for the protector to raise the same upwardly as soon as the first person descending the pole reaches the bottom thereof, whereby to elevate the protector into an out-of-the-way position so as not to impede the movements of the persons after reaching the bottom of the pole.

A further object of the invention is to provide a device of this character of simple and practical construction, which is efficient and reliable in operation, relatively inexpensive to manufacture, and install in operative position with respect to the pole slide, and which is otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view with parts broken away and shown in section.

Figure 2 is a sectional view taken substantially on a line 2—2 of Figure 1.

Figure 3 is an enlarged fragmentary sectional view illustrating the latch mechanism.

Figure 4 is a fragmentary sectional view taken on the line 4—4 of Figure 3.

Referring now to the drawing in detail, wherein for the purpose of illustration I have disclosed

a preferred embodiment of the invention, the numeral 5 designates a pole slide of conventional construction which rises from the ground floor 6 of a building upwardly through an opening 7 in the second floor 8 of the building, the opening 7 being of a size suitable for accommodating a person for sliding downwardly on the pole 5 in a manner commonly practiced by firemen and other persons desiring to quickly descend from an upper floor to a lower floor of a building.

A cylindrical sleeve or protector 9 surrounds the pole 5 and is open at each end, the sleeve or protector being of a size sufficient to accommodate a person descending on the pole 5.

15 A plurality of vertical guide rods 10 extend downwardly from the upper floor 8 to a position below the upper edge of the sleeve 9, the rods 10 being slidably received in notches 11 at the outer edge of the flared upper end 12 of the sleeve 9, the sleeve being adapted to slide vertically on the guide rods 10 in spaced relation from the pole 5.

To the upper edge of the sleeve 9 is attached a cable 13 extending upwardly over pulleys 14 and to the other end of which is attached a weight 15.

A trip cord 16 also has one end attached to the cord or cable 13 and extends downwardly over a pulley 17 and around a pulley 18 attached to the lower floor 6 in a direction toward the lower end of the sleeve 9. The lower end of the trip cord 16 is provided with a ring 19 adapted for engagement by a pivoted hook 20 pivotally attached to the floor 6 by means of a pin 21, the rear end of the hook being formed with a finger 22 extending under one edge of a platform 23 at the bottom of the pole 5 and enclosed within the lower end of the sleeve 9. The platform 23 is yieldably supported in an elevated position on a plurality of springs 24.

In the operation of the device, the sleeve 9 is normally retained in its lowermost position by the trip hook 20 engaging the ring 19 which secures the weight 15 in its raised position, as shown by the full lines in Figure 1 of the drawing.

The first person descending the pole 5 will strike the platform 23 and thus raise the trip hook 20 upwardly out of engagement with the ring 19, thereby to release the weight 15 and which pulls the sleeve 9 upwardly into a position at the top of the pole 5, as indicated by the dotted lines in Figure 1.

The sleeve 9 is thus removed out of the way 55 of persons descending the pole 5. The persons

descending the pole 5 slide downwardly through the sleeve to the lower end of the pole.

Should the trip device 20 fail to function, persons descending the pole 5 into the sleeve 9 may leave the sleeve by means of a door 25 in one side thereof, the door being hingedly mounted along one vertical edge, as indicated at 26, and adapted for outward swinging movement, as indicated in Figure 2 of the drawing.

From the foregoing, it will be apparent that the sleeve 9 serves as a protector for persons who might be standing on the floor 6 adjacent the bottom of the pole 5 so that persons descending the pole will not strike any one at the lower end thereof.

It is believed the details of construction, operation and advantages of the device will be readily understood by those skilled in the art without further detailed explanation.

It will be understood that various changes in the construction and arrangement of the parts forming the invention may be resorted to without departing from the spirit of the invention or the scope of the appended claims.

Having thus described the invention, what I claim is:

1. A protector for pole slides comprising a cylindrical member open at each end and surrounding the pole in spaced relation therefrom and adapted to receive persons sliding down the pole, counterbalancing means for the protector, and trip means actuated by a person descending the pole and operatively connected to said counterbalancing means for releasing the latter to raise the protector into an elevated position.
2. A pole slide protector comprising a cylindrical member open at each end and surrounding the pole, vertical guide means slidably engaged by said cylindrical member, counterbalancing means connected to the cylindrical member for raising the latter, a trip for said counterbalancing means normally securing the cylindrical member in its lower position, and a spring-supported platform at the lower end of the pole within said cylindrical member and actuated by a person descending the pole to release the trip for raising said cylindrical member above the lower portion of the pole.

WILLIAM L. SEIDE.
